UNITED STATES PATENT OFFICE.

HERBERT A. CORBETT, OF AUBURN, NEW YORK, ASSIGNOR TO COLUMBIAN ROPE COMPANY, OF AUBURN, NEW YORK, A CORPORATION OF NEW YORK.

PLAITING, BRAIDING, AND TWISTING MACHINE.

Application filed May 23, 1928. Serial No. 280,085.

This invention relates to improvements in cordage machines, and particularly to a machine for the production of braided or plaited ropes, especially braided rope structures such as are used for clotheslines, sash cords, and the like.

In most, if not all, prior braided ropes, there has been used at the center thereof a solid core, around which the strands or load bearing members of the rope are braided in the form of a covering. The present machine, however, has been so devised that the braided rope product produced thereby will be formed substantially solid, solely and entirely by the strands of which it is composed, thereby eliminating the use of a filler or central core member.

Another object of the invention is to provide a rope machine in which all the strands of the rope produced thereon are interlocked, one with another, whereby if one strand is broken, it is impossible for the same to ravel, due to the fact that it is locked in place at all times by other strands of rope.

A still further object is the production of a rope machine on which any size of rope may be braided, using any number of multiple strands or threads. In the present machine, it is also possible to change the tension or speed of delivery, thereby governing the lay of the strands and rendering the machine capable of use for the production of braided products, especially adapted to comply with various usages.

Again, braided ropes of the prior art frequently have drawn and cut-in strands or threads. The present machine eliminates all possibility of having cut-in or drawn strands or threads, and for this reason it is practically impossible for braided products, in any way, to get out of original shape. Furthermore, by not having cut-in strands, the braided product will be of considerably greater strength proportionate to the number of strands used.

Another feature of the present apparatus resides in the fact that it is not necessary that all of the bobbins carrying the strands be in motion at all times during the operation of the machine. In prior braiding machines, all the bobbins are continuously in motion, passing around what might be termed the longitudinal axis of the core member of the braided rope being produced, with the result that the several strands are braided around that

central core member. It is believed that this is typical of all braiding machines of the prior art. In the present instance, however, this is not true, because the strands are not braided together around a central core member, 60 but are passed from one side of the rope to the other. As a consequence, it is only necessary that two bobbins of the entire set of bobbins of the machine be in motion at any one time. In other words, in the operation of the 65 present machine, two bobbins are simultaneously passed from one side of the machine to the opposite, so that the strands being fed therefrom make a complete cross through the center of the rope being produced. During 70 this manipulation of two bobbins, all the remaining bobbins are stationary, but after this operation has been perfected, two other bobbins are similarly actuated, this method of operation continuing during the manufac- 75 ture of the rope.

In view of this, the power required for the operation of the machine is greatly reduced, and the vibrations set up by the masses constituting the carriers, bobbins and other moving parts are also reduced, and naturally the life of the machine is considerably increased. This arrangement of passing the bobbins in pairs from opposite sides of the machine so that the strands being fed therefrom cross 85 through the center of the rope also results in the plait or braid of the strands being built up much faster, so that in a given period of time, it is believed that the present machine will produce a greater quantity of cordage 90 than the machines of the prior art.

With these and other objects in view, the invention consists in certain novel details of construction and combinations and arrangements of parts, all as will be hereinafter more 95 fully described and the novel features thereof particularly pointed out in the appended claims.

In the accompanying drawings:

Fig. 1 is an elevational view of the machine embodying the present improvements;

Fig. 2 is a horizontal sectional view on the line 2—2 of Fig. 1;

Fig. 3 is a vertical sectional view on the line 3—3 of Fig. 2;

Fig. 4 is a horizontal sectional view on the line 4—4 of Fig. 3;

Figs. 5, 6, and 7 constitute a series of views illustrating three different positions assumed by the bobbin manipulating devices during 110

the cycle of operations of the machine, Fig. 5 showing the positions occupied by the parts at a point just previous to the time at which they occupy the positions in which they are 5 illustrated in Fig. 4, and Figs. 6 and 7 illustrating the positions assumed by the parts after passing from the positions shown in Fig. 4;

Fig. 8 is a detailed elevational view of the 10 strand feeding mechanism of the machine;

Fig. 9 is a detailed vertical sectional view, illustrating one of the bobbin carriers or supports;

Fig. 10 is a horizontal sectional view on the 15 line 10—10 of Fig. 9;

Fig. 11 is a similar view on the line 11—11 of Fig. 9;

Fig. 12 is a diagrammatical layout illustrating the movements of the bobbins during 20 a cycle of operations of the machine, where a braided rope is being produced;

Fig. 13 is an elevational view of a section of 25 braided rope produced on the present machine;

Fig. 14 is a view similar to Fig. 12, showing the movements of the bobbins during the production of a plaited rope such as shown in Fig. 15;

Fig. 15 is an elevational view of a section of 30 plaited cordage produced on the machine;

Fig. 16 is a transverse sectional view of the section of rope shown in Fig. 13; and

Fig. 17 is a similar view of the section of 35 rope illustrated in Fig. 15.

In the machine illustrated in the present instance, there is a main frame comprising standards 10, on which is supported what will 40 be termed a top cam plate 11 and a guide ring 12, the cam plate being of circular formation and occupying a central opening in the guide ring, so that a circular guideway 13 is provided between said plate and ring through 45 which the stems or spindles 14 of the carriers 15 for the bobbins 16, project. While the machine may, of course, be varied in construction, so far as the number of bobbins or strands to be used is concerned, in the present instance, the machine is provided with a set of eight bobbins and bobbin carriers equidistantly spaced around the circular guideway 13. The several bobbin carriers and the movements thereof are similar to one another, so that the ensuing description will be limited 50 to one set of bobbin actuating devices and the movements of one pair of bobbins.

It is, of course, necessary to draw the material, i. e., the strands or rope forming elements, from the bobbins at the proper speed 60 to produce a finished product having the desired appearance, and while this portion of the apparatus forms no part of the present invention, a rather detailed description of the drive or strand feeding mechanism will be given. Referring particularly to Figs. 1 and 65 8, power from any suitable source is trans-

mitted to main drive shaft 17, on which is mounted fast and loose pulleys 18, 18^a. Main drive shaft 17 is journaled in suitable bearings formed in brackets on the main frame of the machine, and at one end carries a 70 beveled gear 19, meshing with a gear 20 mounted on a vertically disposed shaft 21, also journaled in bearings on the frame 10.

At the upper end of shaft 21, there is a worm 22 cooperating with a worm wheel 24, 75 mounted on a stub shaft 25 which also carries a gear 26, meshing with a somewhat larger gear 27 on a shaft 28. Shaft 28 also has

mounted thereon a gear 29, meshing with a gear 30 on shaft 31 horizontally disposed 80 above the upper portion of main frame 10. This shaft 31 carries the grooved member 32,

which, for convenience, will be termed the driven capstan, while the idle capstan 33, 85 of similar grooved design, is fixed on a shaft immediately above capstan 32, this idle capstan being driven by material passing over the same from the driven capstan. Drive

shaft 31, with the driven capstan, also has mounted thereon a sprocket 34, which, 90 through a chain 35, drives a sprocket 36 securely fastened on a shaft 37 journaled in a rearward extension 38 of the machine frame.

This capstan structure, including bracket 38, 95 is supported by a cross 39 and upright members 40, securely mounted on the upper portion of the machine. On shaft 37, in bracket

38, there is a finger gear 41 meshing with a finger gear 42, mounted on a stub shaft 43, 100 which is supported in bracket 38, being held in place by a yoke 44, but capable of riding freely in up and down position in said bracket. Yoke 44 is held in down position

on the finished product at the desired tension by a spring 45, which can be adjusted by suitable means, such as adjusting screw 46. Shaft 43 also carries a top tension roll 47, and 105 shaft 37 carries the bottom roll 48. The strands passing from the bobbins 16, are shown diagrammatically at 49, said strands passing through the capstan devices and the upper and lower tension rolls 47, 48, in accordance with the usual practice.

A further detailed description or illustration of the capstan construction is deemed 110 unnecessary, as neither it nor its driving connection, which has been described, constitute any part of the present invention, and have simply been shown and described to the above extent primarily for the purpose of setting forth a complete operative machine.

Top cam plate 11 is rotatable on a post 50, mounted in a bottom supporting bracket 51 of the main frame and on said post 50 there

is a sleeve 52, to the lower end of which there 115 is keyed a gear 53 supported between anti-friction elements 54 and 55. At the upper

end of said sleeve there is keyed a second but smaller gear 56. Intermediate said gears 120 53 and 56 and rotatable on said sleeve, there

is a gear 57, which is keyed to the lower end of gear 56, and which is in mesh with a gear 58, 125 mounted on a post 59, which is journaled in a bearing in the main frame.

Intermediate gear 57 and gear 58 there is a gear 59, which is keyed to the upper end of gear 56, and which is in mesh with a gear 60, 130 mounted on a post 61, which is journaled in a bearing in the main frame.

is a supporting plate 57, in which is mounted at diametrically opposite points with respect to the axis of post 50, a pair of stub shafts 58 whose upper ends have mounted thereon 5 cams 59 positioned in more or less circular recesses in top cam plate 11 so as to form supplemental guideways 60. These supplemental guideways extend inwardly from the edge of cam plate 11, and form a continuation 10 of main guideway 13 at the periphery of top cam plate 11.

Rotatable on each stub 58, there is a cam ring 61 having an extended hub portion 62 on which is mounted a gear 63. Intermediate 15 the gear 63 of each cam plate member 61 and the gear 56 on sleeve 52, is an idler gear 65, which rotates on a shaft 66, mounted in cam plate 11 and supporting plate 57.

Stubs 58, stub shafts 66, and spacers 66^a 20 rigidly connect top cam plate 11 and lower supporting plate 57 and mounted on said stub shafts 58, 66 and spacers 66^a is a bottom cam plate 64. This bottom cam plate 64 also has therein a guideway 67 which receives the 25 lower ends of the spindles 14 of the bobbin supporting plates 15 the configuration of the ways in said plate 64 corresponding to ways 13 and 60. Each spindle 14 has a camming member 68 adjacent its lower end practically 30 resting on the bottom cam plate 64 and each also has a plate-like collar 69, which prevents wobbling or tilting of the carrier plate 15. As shown in Fig. 10, each plate 15 has a depression or recess 70 therein for the reception 35 of the bobbin 16. That portion of each spindle 14 between the supporting plate 69 and the camming member 68 is adapted to be periodically received between the fingers 71 of bobbin carrier fork members 72 also mounted 40 on the hub portion 62 of cam members 61 on the camming members 68, as will be later described.

As has been mentioned, in the present machine there are eight bobbins supported on a 45 corresponding number of bobbin supporting plates 15, and it has also been stated that only two of these bobbins are moved at a time, the remaining six being stationary.

Normally, the spindles 14 of the bobbin 50 supporting plates 15 are positioned in depressions 73 in a bobbin carriage or ring plate 74 mounted on the machine frame and which forms one wall of way 13, but at the proper time the spindles of the two carriers 55 15 which are to be moved in the making of the rope, are caused to move out of their respective depressions 73 sufficiently far enough inwardly toward post 50 as to be engaged by the fingers 71 of the bobbin carrier fork members 72, so that upon rotation of fork members 72 on stub members 58, the two spindles to be moved will be carried into the auxiliary guideways 60, whereby they may be passed circumferentially around the camming plate, 60 past the bobbins which are remaining sta-

tionary, until they have been transferred to points diametrically opposite those which they originally occupied. In other words, they exchange positions with one another. These results are accomplished by means of motion imparted to cam member 61 through gear 53, sleeve 52, gear 56, gears 65 and gears 63 on the hub of cam plate member 61 which also carries the bottom cam plate 64 and the forked member 72. For moving the two spindles of the two bobbins to be transported around guideways 13 into position to be engaged by forked members 72 as just mentioned, each cam plate 61 has a cam slot 75 in its periphery in which rides a cam roller 76 carried on a trip 77, slidably secured in bottom cam member 64 and forming a portion of the wall of guideway 67 at diametrically opposite points therein.

When the trip members 77 are in their lowest position, the outer wall of guideway 67 in bottom cam plate 64 is substantially unbroken, so that none of the spindles 14 will be disturbed, but when said trip members 77 are lifted, as shown in Fig. 3, they form more or less of an obstruction which causes the lower portion of the bobbin spindles to be moved radially inward with respect to the cam plate members, thereby positioning said spindles at a point where they will be engaged by the fingers 71 of the bobbin carrier fork members 72, the extreme lower portion of spindles 14 having curved lateral extensions 78 adapted to engage said pickup trip 77 and facilitate this movement radially inwardly of the guideways, as well as to give a rotary movement to the same.

For driving gear 53, there is a gear 79 journaled on post 80 in bottom bracket 51 and said gear 79 meshes with a gear 81, keyed to the hub portion of an inwardly beveled pinion 82, journaled on a stud 82^a in said bracket. Said gear 82 is adapted to be driven by an intermittent gear 83 fast on a stub shaft 84 which is journaled in bearing brackets 85, 85^a of the machine frame. This stub shaft 84 carries a gear 86 meshing with a gear 87 on main drive shaft 17. With this chain of driving mechanism, sleeve 52, carrying gears 53 and 56, will be intermittently driven for purposes which will presently appear.

For continuously driving or rotating the lower cam plate 64, and, consequently, the supporting plate 57 and upper cam plate 11, said bottom cam plate 64 is provided with gear teeth at its periphery, adapted to mesh with a gear 88 journaled on a post 89 in the machine frame and bracket 85. Keyed to the hub of gear 88 is a beveled gear 90 which engages beveled gear 19 on main drive shaft 17, so that the bottom cam plate 64 is continuously driven during the operation of the machine. As has been said, this results in the continuous rotation of supporting plate 57 and the upper cam plate 11, because bottom

cam plate 64 is carried on studs 58, which are mounted in the supporting plate 57 and said supporting plate 57 and upper cam plate 11 are rigidly connected by the posts 66 on which 5 the idler gears 65 are mounted, and the additional posts 66^a.

The operation of the machine, as thus described, is as follows:

Referring to Figs. 1 to 7 and 12, and assuming that the two spindles 14 illustrated in Fig. 4 correspond to the two spindles that are about to enter guideway 60 in Fig. 2, and that they correspond to the spindles indicated *a*, *a'*, in the diagrammatical illustration of 15 Fig. 12, it will be seen that the trip members 77 have caused the camming members 68 on spindles 14 to be turned somewhat inwardly, so to speak, and the spindles 14 themselves have been moved radially inward so as to be 20 engaged by the fingers 71 of the bobbin carrier forks 72.

This action is illustrated in Fig. 5, which shows the parts in the positions they occupy immediately before they assume the positions 25 in which they are shown in Fig. 4. In said Fig. 5, as indicated by the arrows, the bottom cam plate member 64, carrying the trip member 77, which has been raised to the position shown in Fig. 4 by the cam 61, is about 30 to engage the camming member 68 on spindle 14, so as to project the latter into the space between the fingers 71 of the bobbin fork carrier 72, which is rotating in a direction opposite to the direction of rotation of bottom cam plate 64. The next step is shown in Fig. 4, 35 where spindle 14 has been partially projected into the space between fingers 71, and one end of the camming member 68 has entered the guideway 60 formed by the cam 59 and upper cam plate 11. In this way, spindles 14 of the two bobbins positioned at diametrically opposite points are moved inwardly 40 so that they may be carried past the other bobbins and transported 180° by the revolving cam plate. In Fig. 6, spindle 14 is shown substantially entirely within the guideway 60 and while the upper and lower cam plates 11 and 64 are being rotated through beveled gears 19, 90, and gear 88, gear 53 on sleeve 52 and gear 56 on said shaft remain stationary. 45 This is due to the fact that the series of teeth on intermittent gear 83 have just passed beyond pinion 82, as shown in Figs. 2 and 3. By reason of the fact that gear 56 is stationary during this period of operation, idler gears 65 rolling around the same causes the 50 two cam members 59 and the forked bobbin carriers 72 to be rotated in the direction of the arrows, as indicated in Figs. 4 to 7.

60 The ratios of the gears are such that by the time the forked carrier 72 with spindle 14 shown at the right in Fig. 4 has been carried 180°, or substantially that distance by cam plate 11, said fork carrier 72 has been rotated to the position shown in Fig. 7, at which

point the bobbin spindle 14 is about to pass out of the guideway 60, into the main or peripheral guideway 13. As shown in said figure, the bobbin cam plate 64 rotating in the direction of the arrow, and the bobbin fork 70 carrier 72 rotating in the direction of the arrow thereon, will result in the bobbin spindle 14 being redeposited in the depression 73. During this movement of each spindle 14 shown in Fig. 4, through an arc of 75 180° around the machine, both of said spindles will have been within the guideway 60, so as not to interfere with the remaining spindles positioned around main guideway 13 and the trip member 77 will have been withdrawn from guideway 67 in bottom cam plate 64 by reason of the fact that the low side of cam slot 75 will have pulled down roller 76, so as to depress said trip member 77. This prevents said trip member 77 interfering with any of the other bobbins during the movement of the two bobbins to opposite sides of the machine. In this way, bobbins indicated *a*, *a'* in Fig. 12 are moved 180° around the machine, as indicated by the arrows in that figure, the rope elements or strands carried by said bobbins thus being caused to cross each other at substantially the center of the rope. The next two bobbins to be similarly actuated are indicated at *b*, *b'*, 90 in Fig. 12, and as the distance from *a'* to *b* is less than the distance required to impart a complete revolution to bobbin fork carrier 72 (*a* to *a'*), it is necessary that some means be provided for accelerating the speed 95 of rotation of said carrier after said carrier has deposited bobbin *a* at position *a'*, and before it reaches position *b* in Fig. 12 to pick up one of the bobbins of the next pair.

It is for this purpose that the intermittent drive through gear 53 is provided. In other words, after bobbin *a* in Fig. 12 has been deposited at *a'*, the teeth of intermittent gear 83 will have again engaged pinion 82, thereby rotating gear 53, gear 79, sleeve 52, and driving gear 56, which meshes with the idler gears 65. As a result, the rotation of the bobbin fork carriers 72 is accelerated, so that by the time the two bottom fork carriers have traveled from position *a'* in Fig. 12 to position *b*, and from position *a* to position *b'*, in said figure, respectively, the fingers 71 of said carrier will have assumed, with respect to bobbin spindles *b*, *b'*, identically 110 the same positions in which they are shown in Figs. 4 and 5, i. e., they will have been given substantially a complete rotation on stub shafts 58, so as to be ready to pick up bobbin carrier spindles indicated at *b*, *b'*, 115 and transport each of them 180° after which they will be redeposited in the main or peripheral guideway 13. In this way, the two strands carried by said bobbins *b*, *b'* will have been caused to cross each other at substantially 120 the center of the braided product.

125 130

The same cycle of operations is then repeated, so as to actuate bobbins c, c' , indicated in Fig. 12, and then bobbins d, d' will be actuated or moved 180° around the cam plate. As a result, each pair of diametrically disposed bobbins is successively picked up and carried 180° , thereby crossing each pair of strands at the center of the braided rope, so that the finished product will be a substantially solid braided rope, even though no solid core member is utilized therein.

As shown in Fig. 13, in the resulting product of these operations each strand not only crosses another at the center of the rope, but each is also securely locked in place so that if one of them should become broken, it is impossible for the rope to ravel. Another advantage of this form of machine is that any number of pairs of bobbins, and, consequently, strands, may be utilized, so as to produce a braided rope of any desired size with any number of multiple or pairs of strands. Again, it is impossible for the strands to be cut in or drawn so that the rope can not get out of its original shape, and the absence of cut in strands results in a greater strength in the rope for a given number of strands. Another feature resides in the fact that only two bobbins are being moved at any one time, i. e., the two that are being transported 180° , all the remaining bobbins remaining stationary during the movement of those two. This results in much less vibration and wear and tear on the machine. Furthermore, by passing the bobbins from one side of the machine to the opposite, making a complete cross through the center of the rope, the braided product may be built up much faster, so that the present machine will produce considerably more rope over a given period of time.

The operation of the machine as thus described results in the production of what is known as braided or plaited cordage, but the machine is also susceptible of use for the production of twisted cordage, such as shown in Figs. 15 and 17. For producing twisted cordage, it is only necessary to change the ratios of gears 53 and 79, and the direction of rotation of the cam plates, as indicated in Fig. 14. In other words, to produce the plaited rope, the bobbins a, a' (Fig. 14) are picked up and transported 180° , as in the previous case, but after they have been re-deposited in the main guideway 13 the ratios of gears 79 and 53 is such as to retard the subsequent rotation of the bobbin fork carriers so that they will not be in a position to pick up the next two bobbins until the parts have traversed an arc of 225° , at which time they will pick up bobbins b, b' , as indicated in Fig. 14. After bobbins b, b' have been moved to diametrically opposite points, the cam plate members are moved another 225° before the bobbin fork carriers 72 have made

a complete revolution, so that bobbins c, c' are then picked up and their positions exchanged, after which the same operations are again repeated, as to bobbins d, d' .

It will, of course, be appreciated that where the number of bobbins is greater or smaller than eight, as illustrated in the present instance, the ratios of the gears for rotating the bobbin fork carriers between the time one bobbin is ejected and the next is picked up, will have to be varied, depending upon the distance said bobbin fork carriers must travel before picking up the next succeeding bobbin.

What I claim is:

1. In a rope machine, the combination of a frame, a rotatable plate on said frame, a plurality of pairs of bobbins from which rope forming strands are fed spaced around said plate, and means for successively moving each pair of diametrically opposed bobbins to exchange positions originally occupied by the same whereby the strands of each pair of bobbins are crossed at the center of the rope being formed.

2. In a rope machine, the combination of a series of pairs of bobbins circumferentially spaced around the axis of said support, each bobbin carrying a rope forming strand or element, a rotatable plate, and means for successively moving diametrically opposed bobbins into engagement with said plate and transporting the same substantially 180° past the remaining bobbins and there disengaging said bobbins from said plate.

3. In a rope making machine, the combination of a rotatable plate having a guideway at the periphery thereof and a pair of supplementary ways extending inwardly from said peripheral guideway, means for supporting a series of pairs of diametrically opposite strand carrying bobbins in said peripheral guideway, and means for successively moving each pair of bobbins into said supplementary way and subsequently returning them to said peripheral way after said plate has completed a one-half revolution.

4. In a rope making machine, the combination of a rotatable plate having a guideway at the periphery thereof and a pair of supplementary ways extending inwardly from said peripheral guideway, means for supporting a series of pairs of diametrically opposite strand carrying bobbins in said peripheral guideway, and means for successively moving each pair of bobbins into said supplementary way and subsequently returning them to said peripheral way after said plate has completed a one-half revolution, the other pairs of bobbins remaining stationary during the movement of each successive pair and the pair being moved past said other pairs during said half.

5. In a rope machine, the combination of a rotatable plate having a circular way therein, a series of pairs of diametrically opposed

5 bobbins from which rope strands or elements are fed disposed around said way, a pair of pickup devices carried by said plate and successively engageable with diametrically opposed bobbins to move the same out of said way, said plate being rotatable to move the 10 picked up bobbins past the remaining bobbins, and said pickup devices being operable to redeposit the picked up bobbins in said way after said plate has made a one-half revolution.

6. In a rope machine, the combination of a rotatable plate having a peripheral guideway, a plurality of diametrically opposed 15 pairs of bobbins disposed around said guideway, and a pair of pickup devices carried by said plate for successively moving each pair of bobbins out of said guideway and returning the same to said guideway after the 20 picked up pair of bobbins has been carried by said plate past the remaining bobbins to exchange the positions originally occupied by said picked up bobbins.

7. In a rope machine, the combination of a 25 rotatable plate having a peripheral guideway, a plurality of pairs of diametrically opposed bobbins disposed around said guideway, a pair of rotatable pickup devices carried by said plate and adapted to engage said 30 pairs of bobbins successively and remove them from said peripheral guideway inwardly of said plate, means for rotating said pickup devices to retain the picked up bobbins inwardly from the periphery of said 35 plate until said plate has been given a one-half revolution, at which time said picked up bobbins are redeposited in said peripheral way, and means for varying the speed of rotation of said pickup devices between the time 40 one pair of bobbins is redeposited in said way and the time the next pair of bobbins is engaged by said pickup devices.

8. In a rope machine, the combination of a 45 rotatable plate having a peripheral guideway and a pair of supplemental circular ways extending from said peripheral way inwardly of said plate, a plurality of pairs of diametrically opposed bobbins disposed around said peripheral way, a pair of pickup devices carried by said plate and adapted to successively engage each pair of bobbins and move the same through said supplemental way while said plate is making a one-half revolution after which the picked up bobbins are redeposited 55 in said peripheral way, the remaining bobbins other than the picked up pair of bobbins remaining stationary during the movement of said picked up bobbins.

9. In a rope machine, the combination of 50 a rotatable plate having a peripheral way and a pair of supplemental circular ways extending inwardly from said supplemental way at diametrically opposed points, a cam plate rotatable with said guide plate and having guideways therein corresponding to the

ways in said plate, a plurality of pairs of diametrically opposed bobbin carriers having spindles extending through the ways in said plates, a pair of pickup devices carried by said rotatable plates, said bobbin carrier spindles being normally disposed in said ways to prevent engagement of said pickup devices therewith, means for successively engaging diametrically opposed pairs of spindles to move them into position to be engaged by 75 said pickup devices, and means for actuating said pickup devices to remove said successive pairs of bobbin carrier spindles from the peripheral way into the supplemental way and redeposit them in said peripheral way 80 after said plates have made a one-half revolution.

10. In a rope machine, the combination of a central post, a plate rotatable on said post and having a peripheral way with a pair of diametrically opposed circular supplemental ways extending inwardly from said peripheral way, a supporting plate rotatable on said post and rigidly attached to said first- 90 mentioned plate, a guideway plate carried by said supporting plate having ways therein conforming to the ways of said rotatable plate, a plurality of pairs of diametrically opposed bobbin carriers having spindles disposed around said peripheral way and projecting into said guideway plate, a forked pickup member supported by said supporting plate, said carrier spindles being normally disposed in said guideways so as to prevent 95 engagement of said forked pickup members therewith, means for successively moving each pair of bobbin carrier spindles into position to be engaged by said forked pickup members, means for rotating said forked pickup members to move such successive pairs of bobbin carrier spindles through the supplemental ways in said rotatable plate and back into the peripheral way after said plate has made a one-half revolution, and means for varying the speed of rotation of said 100 forked pickup members between the time one pair of bobbin carrier spindles is deposited in said peripheral way and the time the next pair of bobbin carrier spindles is 105 engaged by said forked pickup members.

11. In a rope machine, the combination of a rotatable plate having a peripheral guideway, a plurality of pairs of diametrically opposed bobbin carriers disposed around said peripheral way from which the rope strands or elements are adapted to be fed, and means for successively moving the bobbin carriers of each pair to exchange the original positions thereof whereby the strands fed therefrom will cross one another at the center of the rope being produced.

12. In a rope machine, the combination of a rotatable plate having a peripheral guideway, a plurality of pairs of diametrically opposed bobbin carriers disposed around said 130

peripheral way from which the rope strands or elements are adapted to be fed, and means for transporting the bobbin carriers of each successive pair around the axis of said rotatable plate to exchange the positions originally occupied by them while the remaining pairs of bobbin carriers remain stationary, whereby the strands or rope elements being fed from each pair of bobbins are crossed at substantially the center of the rope being formed.

13. In a rope machine, the combination of a rotatable plate having a peripheral guideway, a plurality of pairs of diametrically opposed bobbin carriers disposed around said peripheral way from which the rope strands or elements are adapted to be fed, and means for moving the bobbin carriers of each pair successively into engagement with said rotatable plate and disengaging said successive pairs from said plate after the same has made a one-half revolution whereby each pair of bobbins exchanges original positions and the strands or rope elements fed therefrom are caused to cross each other at the center of the rope being formed.

14. In a rope machine, the combination of means for supporting a series of circularly arranged diametrically opposed bobbin carriers, and means for successively engaging each pair of carriers and moving them inwardly of the remaining bobbins and transporting them to points diametrically opposite their original positions.

15. In a rope machine, the combination of means for supporting a series of circularly arranged, diametrically opposed bobbin carriers, and means for successively transporting the bobbin carriers of each pair to points diametrically opposite their original position, the remaining bobbin carriers being stationary during the movement of each pair of carriers.

16. In a rope machine, the combination of means for supporting a series of circularly arranged diametrically opposed pairs of bobbin carriers, a pair of normally inoperative pickup devices revoluble concentrically with the circularly arranged carriers, and means for successively engaging the carriers of each pair and moving the same into position to engage said pickup devices, and means for revolving said pickup devices to transport the carriers of each pair to positions diametrically opposite their original positions.

17. In a rope machine, the combination of a pair of rotatable plates having corresponding peripheral and inwardly extending guideways, a plurality of pairs of diametrically opposed bobbin carriers circularly arranged in said guideways, a pair of pickup devices carried by said plates, a pair of trips adapted to successively engage each pair of carriers and position them in the path of said pickup devices, and means for rotating said plates and pickup devices to transport the picked

up carriers to positions in said guideways diametrically opposite their original positions.

18. In a rope machine, the combination of a pair of rotatable plates, having corresponding peripheral and inwardly extending guideways, a plurality of pairs of diametrically opposed bobbin carriers circularly arranged in said main guideways, a pair of pickup devices carried by said plates, a pair of normally inoperative trips, means for actuating said trips to successively engage a pair of carriers and move them into position to be engaged by said pickup devices, and means for revolving said plates and pickup devices to transport the picked up carriers to positions in said guideways diametrically opposite their original positions, said trips being rendered inoperative after each pair of carriers is picked up whereby the other pairs of carriers remain stationary.

19. In a rope machine, the combination of a pair of rotatable plates having corresponding main and supplemental guideways, a plurality of pairs of diametrically opposed, stationary bobbin carriers circularly arranged in said main guideway, a pair of pickup devices carried by said plates, a pair of trips, means for intermittently projecting said trips into the main guideway of one plate to engage a pair of diametrically opposed carriers and move them into position to be engaged by said pickup devices, means for rotating said pickup devices to move the said pair of carriers into the supplemental ways of said plates, and means for revolving said plates while a pair of carriers are in supplemental ways to transport said carriers past the remaining carriers to positions diametrically opposite their original positions.

20. In a rope machine, the combination of a pair of rotatable plates having corresponding main and supplemental guideways, a plurality of pairs of diametrically opposed, stationary bobbin carriers circularly arranged in said main guideway, a pair of pickup devices carried by said plates, a pair of trips, means for intermittently projecting said trips into the main guideway of one plate to engage a pair of diametrically opposed carriers and move them into position to be engaged by said pickup devices, means for rotating said pickup devices to move the said pair of carriers into the supplemental ways of said plates and return them to said main guideways after said plates have made a one-half revolution, and means for rotating said pickup devices at a different rate of speed after said carriers have been returned to said main guideways.

21. In a rope machine, the combination of a pair of constantly rotating plates having corresponding main guideways and supplemental guideways intersecting said main guideways, a plurality of pairs of diametrically opposed bobbin carriers circularly ar-

ranged in said main guideways, means for successively moving each pair of carriers into the points of intersections of said ways, a pair of pickup members adapted to engage 5 each pair of carriers positioned at said intersection, means for actuating said pickups to move said carriers through said supplemental ways and return them to said main guideways upon a one-half revolution of said plates, 10 and means for actuating said pickups at a different rate of speed after said pair of carriers have been returned to said main guideways and before said trips have positioned another pair of carriers at said points 15 of intersections.

22. In a rope machine, the combination of a pair of constantly rotating plates having corresponding guideways with supplemental ways intersecting said main ways, a plurality 20 of stationary pairs of diametrically opposed bobbin carriers positioned in the main ways of said plates, means for successively moving the pairs of carriers toward the points of intersection of said ways, a pair of forked 25 pickup devices, means for rotating said pickup devices at a predetermined speed to move the forks thereof through said points of intersection to pickup the carriers positioned therein and move them through said supplemental ways and return them to the main 30 ways during a one-half revolution of said plates, and means for rotating said forked pickup devices at a different rate of speed after said carriers have been returned to the 35 main ways and until the forks of said devices again pass through the intersections of said ways.

23. In a rope machine, the combination of a central post, a pair of plates rotatable on 40 said post and provided with corresponding circular guideways, means for supporting a plurality of pairs of diametrically opposed bobbin carriers in said ways, and means for successively moving each pair of carriers inwardly of said plates toward the axis of rotation thereof and out of said guideways and exchanging the positions of said carriers, the other pairs of carriers remaining stationary 45 during the transposition of each pair.

24. In a rope machine, the combination of a central post, a pair of plates rotatable on 50 said post, each having a main circular guideway and supplemental ways extending inwardly from said main way, means for supporting a plurality of pairs of bobbin carriers 55 diametrically opposed to each other in said main way, means for constantly rotating said plates, a pair of stub shafts movable with said plate, a pick-up device on each stub shaft, 60 means for rotating said pick-up devices dur-

ing a one half revolution of said plates to remove a pair of carriers from said main way through the supplemental ways and return them to said main way, a pair of cam-actuated trips in the main way of one plate for moving a pair of carriers into position to be engaged by said pick-up devices, and a cam journaled on said stub shaft for actuating said trip. 65

25. In a rope machine, the combination of 70 a central post, a pair of plates rotatable on said post, each having a main circular guideway and supplemental ways extending inwardly from said main way, means for supporting a plurality of pairs of bobbin carriers 75 diametrically opposed to each other in said main way, means for constantly rotating said plates, a pair of stub shafts movable with said plate, a cam member journaled on each stub shaft, a gear secured to said cam, a gear 80 journaled on said post from which motion is transmitted to the cam gear, intermittently operable driving means for rotating the gear on said post, a forked pick-up device secured to said cam, a trip actuated by each cam for 85 successively moving the carriers of the several pairs into position to be engaged by said forked pick-up devices, the speed of rotation of said cams and pick-up devices being such that the carriers engaged by said devices are 90 removed from the main ways through said supplemental ways and returned to said main ways during a one-half revolution of the plates. 95

26. In a rope machine, the combination of 100 a central post, a pair of plates rotatable on said post, each having a main circular guideway and supplemental ways extending inwardly from said main way, means for supporting a plurality of pairs of bobbin carriers 105 diametrically opposed to each other in said main way, means for constantly rotating said plates, a pair of stub shafts movable with said plate, a cam member journaled on each shaft, a gear secured to each cam, a gear journaled on said post from which motion is 110 transmitted to said gears on said cams, a pick-up device on each cam, a trip for each pick-up device operated by said cams to move a pair of carriers into position to be engaged 115 by said pick-up devices, and drive means connected to the gear on said post to impart a complete revolution to the same and to said cams and pick-up devices during a one-half revolution of the plates on said post, said drive means being operable only during each alternate rotation of said cams and pick-up devices. 120

HERBERT A. CORBETT.
